UNITED STATES PATENT OFFICE.

THOMAS WHITE AND JOHN MILNE, OF NEW YORK, N. Y.; SAID MILNE
ASSIGNOR TO SAID WHITE.

TROUSERS-STRETCHER.

SPECIFICATION forming part of Letters Patent No. 396,380, dated January 15, 1889.

Application filed May 8, 1888. Serial No. 273,241. (No model.)

To all whom it may concern:

Be it known that we, THOMAS WHITE and JOHN MILNE, citizens of the United States, and residents of New York, in the county of 5 New York and State of New York, have invented certain new and useful Improvements in Trousers-Stretchers, of which the following is a specification.

Our invention relates to that class of trousers-stretchers in which two pairs of clamping-bars are combined with an intermediate sectional brace; and it consists of certain novel 10 features of construction, hereinafter fully described, for permitting easy and effective adjustment of the parts.

In the accompanying drawings, Figure 1 represents a front view of a trousers-stretcher embodying our invention. Fig. 2 represents a side view thereof. Fig. 3 represents a detail 15 view of a portion of one pair of the clamping-bars on a larger scale than in the previous figures. Figs. 4 and 5 represent detail views of the bearings for the movable clamping-bar. Fig. 6 represents an end view of the 20 movable clamping-bar. Fig. 7 represents a cross-section of the brace on the line $x-x$, Fig. 1. Fig. 8 is a detail view of the yoke J.

Similar letters indicate similar parts.

The letters A A' indicate the two members 25 of either pair of clamping-bars, and B B' two sections of a brace, each carrying one pair of said bars. The bar A is fixed rigidly to either brace-section B B', while the bar A' is movable, it being mounted in bearings C C' on the opposite ends of said fixed bar by means of pivots $d d'$, Fig. 3, to be adjusted by 30 that means in relation to the fixed bar. Said pivots $d d'$ of the movable bar are eccentric thereto, the bar being usually in form of a roller, and the bearings C C' are composed of 35 plates, one of which, C, has a longitudinal slot, e, to receive the proper pivot and is bent outward at the free end to a hook shape, as shown, while the other, C', has a longitudinal 40 groove, f, on the inner surface extending from the pivot-hole g to the free end thereof. The pivot d , resting in the slotted bearing C, is headed, as more clearly shown in Fig. 3, for 45 its retention in the slot, the other pivot, d' , being left plain to permit its removal from its bearing.

The brace-sections B B' rest against each other, and one section, B, has spring arms or clasps h on the longitudinal edges to engage the corresponding edges of the other section, 55 and has also a series of notches, i, in the outer or under surface, while the section B' carries a swinging yoke, J, to embrace the section B and engage with its notches, said yoke being held in place by a strap, l, secured to the 60 proper part.

When the stretcher is applied to use, the movable clamping-bar A' of each pair of bars is swung away from the fixed bar A on the headed pivot d in the slotted hook-shaped 65 bearing C, the other bearing, C', being first sprung outward to free the plain pivot d' , and the legs of the trousers are laid on the fixed bar. The movable bar A' is then readjusted, the pivot d' being guided to its place in the bearing C' by the groove f, and said bar is turned on the pivot, when, due to the eccentric 70 position of the latter, the movable bar gradually approaches the fixed bar, with the effect of firmly clamping the trousers between 75 the two bars. When the movable bar A' is swung away from the fixed bar A, the headed pivot d travels in the slot e of the bearing C in the line of said bearing, which, being hook-shaped, permits said pivot, together with the 80 movable bar, to be entirely reversed in its horizontal position without disconnecting the pivot from the bearing, while when the movable bar is in normal position the headed end of the pivot rests approximately in the height 85 of the hook, which thus constitutes the bearing proper. During said clamping operation the brace-sections B B' are to be disconnected from each other—namely, by removing the section B' from the clasps h of the section B— 90 and one section is brought to an angle in relation to the other, so as to lessen the distance between the two pairs of clamping-bars. The brace-sections B B' are now replaced upon each other by forcing the section B' into 95 the clasps h, while the swinging yoke J is at the same time inserted in one of the notches i to hold the sections lengthwise, whereby the legs of the trousers are stretched and retained in a stretched condition.

In some cases the notches i may be dispensed with and the upper interior surface of

the yoke J may have serrations o, as shown in Fig. 8, for engaging the surface of the bar B.

What we claim as new, and desire to secure by Letters Patent, is—

- 5 1. In a trousers-stretcher, the combination, with a suitable brace, of clamping-bars, one fixed and the other movable, eccentric pivots on the ends of the movable bar, and bearings for said pivots on the fixed bar, one such bearing being slotted and hook-shaped and the pivot therein being headed to permit the movable bar to be swung away from the fixed bar without disconnecting said pivot from the bearing, and the other bearing constructed to 10 permit removal of the pivot therefrom, substantially as and for the purpose described.
- 15 2. In a trousers-stretcher, the combination,

with a suitable brace, of clamping-bars, one fixed and the other movable, eccentric pivots on the ends of the movable bar, and bearings 20 for said pivots on the fixed bar, one such bearing being slotted and hook-shaped and the pivot therein being headed, for the purpose specified, and the other bearing having a groove extending from the pivot-hole to the 25 extremity thereof to act as a guide for the proper pivot, substantially as and for the purpose described.

THOMAS WHITE.
JOHN MILNE.
